WESTINGHOUSE ELECTRIC & MANUFACTURING COMPANY, A CORPORATION OF
PENNSYLVANIA.

ANTENNA SYSTEM FOR ELECTRIC WAVES.

Application filed October 31, 1921, Serial No. 511,776, and in Germany November 2, 1920.

The invention applies to an antenna-system for electric waves which permits of general use, especially for telegraphic or telephonic communications on vehicles. The 5 invention includes combining one or more open antennæ with one or more closed antennæ. As open antennæ, we prefer the usual antenna wires while loop antennæ are most suitable for the closed form.

10 It is an object of this invention to provide a radiating system which shall effectively use both the electrostatic and the magnetic components of the radiation.

15 It is a further object of this invention to combine into one radiating system a loop antenna and an antenna of the open-circuit type.

20 It is a further object of this system to provide a radiating device which is particularly adapted for use upon vehicles, especially where there is a conductor along the wayside for communication with such vehicles.

25 Other objects of this invention and details of the construction employed will be apparent from the following description and the accompanying drawing, wherein

Figure 1 is a diagram showing the arrangement of the conductors in one form of our device.

30 Fig. 2 is an illustration of the antennæ and the wayside conductor, showing the same connected to a sending apparatus, and

Fig. 3 shows a modification of one of the antennæ in Fig. 2.

35 As shown in the drawings, an open antenna *a* is connected to the grid circuit of a vacuum-tube device *c* and is fitted, if required, with an extension coil *s* and a shortening condenser *k*. By means of these, the 40 antennæ may be tuned to the incoming waves. A closed antenna, comprising a loop *r*, is connected to the grid circuit of the same tube. A tuning condenser *C* is connected across the ends of the loop and may be regarded as constituting a part of the closed antenna.

45 As shown in the diagram the wire of the open antenna is connected to the loop antenna, while the tuning means of the open antenna are connected to another point of the 50 loop. Both antennæ are thus connected in parallel to the grid circuit of the vacuum-tube device. At a suitable place, preferably within the loop, an additional coil *z* may be inserted for various purposes. The coil *z* may

be used for finer adjustment of the self-inductance of the loop *r*, or as a coupling coil for the grid or anode circuits of the vacuum tube. A coil in the plate circuit (not shown) may co-operate with *z* to produce the coupling. A condenser *b*, with parallel resistance *w*, is also connected to the grid circuit for various purposes. For one, it gives a definite bias on the grid and permits the sensitiveness of the vacuum tube to be adjusted at will. Also it is likely to have an 60 advantageous effect in cases of repeated amplification by the same tube. A telephone transformer *t* is inserted directly in the anode circuit. Of course, several tubes may be used instead of a single one and these again may 65 be arranged for high or low-frequency amplification or for both. Heterodyne reception may be used, if desired, in connection with these antennæ.

70 While no explanation of the reasons for the efficiency of this arrangement is given here, it may be noted that the loop causes the particularly favorable coupling of the electromagnetic field while the open antenna receives the electrostatic waves.

75 Such an arrangement is particularly suitable on carriages or cars for transmission to wires strung parallel to the wayside. The effect probably is that the loop brings about the electromagnetic coupling with the conducting line, while the open antenna influences or receives the electrostatic waves.

80 The open antenna system may, in the case of vehicles, consist of wires arranged above the roof, along the sides, or under the bottom 90 of the car, while one or more loop antennæ may also be fitted on the same or another car. The wires of the open antenna are best arranged parallel to one another, the ends being all connected together or connected in 95 groups. The leads are preferably connected to the center points of all or of some of the wires.

Fig. 2 shows one form of the last mentioned 100 arrangement. There *a* are the open wires and *r* is a loop. Both are connected to one or more vacuum tubes, as shown in Figure 2. The circuit arrangement shown in Figure 2 is especially suitable for transmitting and, for this reason, the antennæ are coupled to an oscillating circuit in the anode connection of the vacuum tube *e*. The favorable effect of this arrangement is apparently due to the consid-

erable increase of capacity in the antennæ as compared with the arrangement heretofore employed on vehicles. By this means, a large antenna capacity, as compared to that of the condenser in the oscillating circuit of the anode connection, is successfully obtained, and, for this reason, a great part of the oscillatory energy produced enters the antennæ and is transferred from there to the line *l* (Fig. 2). Experience has shown that there is a limit beyond which increased capacity brings no increase of the desired result. In this case also, the open antenna will influence the electrostatic and the closed antenna the magnetic field. A special advantage of this arrangement is that a large amount of energy is delivered to the line *l*, whatever the position of the antennæ. Often this energy is of the same amount in all positions of the antennæ. Instead of leading every single wire of the open antenna to the vacuum tube, all the wires can be connected together (Fig. 3) and the connecting wire be led to the generator of the oscillations. It has been found to be of special advantage to provide the connecting points at the center of the open antenna wires so that the influence of their two halves in regard to the loop is balanced and any additional influence of the loop is avoided. The loop itself may be fixed to the vehicle sideways, across same on top, or in any other suitable manner. If desired, a plurality of loops may be provided.

The tuning appliances, as per Figure 1, besides lengthening or shortening the open antenna, have also the effect of adjusting the phase displacement of currents in the open antenna, relative to those in the closed antennæ, which may be due especially to the different capacities or the self-inductances or to both in the different kinds of antennæ.

It is also possible to use the combined antennæ of this invention alternately for transmitting and receiving, by providing corresponding switches or by inserting multiple coupling appliances leading on the one side to the grid circuit and on the other to the anode circuit. In this arrangement, selective circuits may be inserted besides the oscillating circuits, or the oscillating circuits may simultaneously act as selective circuits.

We claim as our invention:

A radiating circuit including an open antenna and a loop antenna connected together, an adjustable reactance means in the open antenna upon the side of said connection opposite the free end of the open antenna, receiving apparatus connected to the radiating circuit and an adjustable capacity connected across the loop antenna between said receiving device and the connection of the two antennæ.

In testimony whereof we affix our signatures.

WALTER NAUWERK.
Dr. FRIEDRICH WALTER.
